SYSTEM OF RADIO COMMUNICATION

Filed Sept. 16, 1926

Inventor:
Henry C. Forbes
By G. E. Gray Atty.

UNITED STATES PATENT OFFICE

HENRY C. FORBES, OF CHICAGO, ILLINOIS, ASSIGNOR TO ZENITH RADIO CORPORATION,
OF CHICAGO, ILLINOIS, A CORPORATION OF ILLINOIS

SYSTEM OF RADIOPHONIC COMMUNICATION

Application filed September 16, 1926. Serial No. 135,826.

My invention relates to systems of radio communication and is of particular use in those systems wherein the sending and receiving stations are not far apart.

5 The system of my invention is especially useful when employed in establishing communication between stations upon locomotives and the cars of a train. The invention is of much service in establishing communication between attendants upon the locomotives and cabooses of freight trains.

While the invention thus finds especial utility, it is not to be limited to any particular use.

It is the object of my invention to include 15 signaling apparatus in the system whereby an operator or attendant at either station may signal an operator or attendant at the other station. Generally speaking, the radio system of communication of my invention employs an antenna, a circuit having means 20 therein for generating and impressing upon said antenna a wave form carrier current, a telephonic circuit including a telephonic transmitter, a signaling circuit, a modulating thermionic valve interposed between said 25 wave form carrier current circuit and said telephonic and signaling circuits, and means included in the signaling circuit serving as a generator of signaling current. In the preferred embodiment of the invention, the 30 means for generating the wave form carrier current and the means for generating the signaling current are in the form of thermionic valves.

35 The signaling apparatus desirably furnishes audible signals, a result which is preferably secured by a modulation of the carrier current wave by a signaling current wave of approximately 800 cycles, the modulations 40 thus impressed upon the carrier current wave at the sending station causing an audible signal at the receiving station and preferably in a loud speaker located at the latter station.

45 Such a signal, in railroad practice, is easily discernible through the rumbling noises made by the moving train and the higher pitched noises such as those caused by steam whistles.

I will explain my invention more fully by 50 reference to the accompanying drawing

which diagrammatically illustrates the preferred embodiment thereof.

In the system illustrated, the antenna 1 is grounded through a winding 2. A winding 3, in conjunction with the winding 2 to which it is inductively related couples the antenna with a circuit in which a wave form carrier current is generated and upon which signaling and telephonic current modulations are adapted to be impressed. This circuit is illustrated as being inclusive of an oscillator in the form of a thermionic valve 4 employing a grid 5, a plate 6, and a filament or cathode 7. The grid is connected with one terminal of the winding 3 by way of the condenser 8. The other terminal of the winding 3 is connected with the plate 6 through the condenser 9. The filament 7 is supplied with current from a battery 10. A source of direct current 11 is connected between the filament 7 and the plate 6 by way of the air core choke coil 12. The conductor 13 by which one pole of the generator 11 and one pole of the battery 10 are connected with the filament 7 is desirably adjustably connected with the winding 3. The antenna 1 is thus coupled with a circuit in which wave form carrier current is generated.

A local telephonic circuit includes a telephonic transmitter 14, the primary winding 15 of an inductive coupler 15-18, a battery 16, and a circuit opening and closing switch arm 17. The secondary 18 of coupler 15-18 has one terminal connected with the grid 19 of a thermionic valve 20, this valve having a plate 21 connected with the conductor 13 and a filament or cathode 22 supplied with current from a battery 23. When the switch 17 is closed and the transmitter 14 spoken into, telephonic current changes are impressed upon the wave form carrier current circuit by way of the thermionic valve 20 which serves to modulate the wave form carrier current under the control of the telephonic circuit. The circuit that includes the grid 19 and the telephonic secondary 18 also includes a signaling secondary 24 whose complementary primary 25 is included in an inducing signaling circuit which also contains a plate 26 of a thermionic valve 27, and the adjust- 100

able switch arm 28. The grid 29 of the valve 27 is connected with the circuit of grid 19 between the windings 18 and 24. The filament or cathode 30 is supplied with current from the battery 23'. The switch arms 17 and 28 are coupled by the switch lever 31 so that when either switch closes the circuit to which it pertains, the other switch opens the circuit to which it pertains. The valve 27 serves to generate wave form signaling current of, say, 800 cycles. The current oscillations thus generated are applied to the grid-filament circuit of valve 20 which includes the windings 18 and 24. The valve 20 is common to the 10 signaling and telephonic circuits and serves to modulate the carrier current circuit under the control of either of these circuits according to the adjustment of the switch lever 31.

Changes may be made without departing 20 from the invention.

Having thus described my invention, I claim:

1. In a radio system of communication, the combination, with an antenna and a circuit 25 having a first thermionic valve therein operating to generate and impress upon said antenna a wave form carrier current, of a telephonic circuit including a telephonic transmitter; a signaling circuit having a second 30 thermionic valve therein operating to generate wave form signaling current; a coupling circuit having a third thermionic valve therein, the output of which is connected with the input circuit of said first valve and the input 35 circuit of which is connected with the input circuit of said second valve; a plurality of transformers, the secondary windings of which are included in the input circuit of said third valve, and the primary windings of 40 which are included, one in the said telephonic circuit and the other in the said signaling circuit; and means operable at will to selectively open one and close the other of said telephonic and signaling circuits.

2. In a radio system of communication, the combination, with an antenna and a circuit 45 having a first thermionic valve therein operating to generate and impress upon said antenna a wave form carrier current, of a telephonic circuit including a telephonic transmitter and a first transformer primary winding; a signaling circuit having a second thermionic valve therein operating to generate a signalling current and having a 50 second transformer primary winding in the output circuit of said second valve; a third thermionic valve operating as a modulator under the control of said telephonic circuit, the output of said third valve being connected 55 with the input of said first valve and the input of said third valve being connected with the input of said second valve and having first and second transformer secondary windings complementary respectively to said first and 60 second transformer primary windings; and 65

means operable at will to close said telephonic circuit and open the output circuit of said second valve, and vice versa.

In witness whereof, I hereunto subscribe my name.

HENRY C. FORBES.
